(57) **CLAIM**

The ornamental design for a pedometer, as shown and described.

DESCRIPTION

FIG. 1 is a top view illustrating our new design for a pedometer according to a first embodiment;

FIG. 2 is a bottom view of the pedometer of FIG. 1;

FIG. 3 is a front view of the pedometer of FIG. 1;

FIG. 4 is a rear view of the pedometer of FIG. 1;

FIG. 5 is a right side elevational view of the pedometer of FIG. 1;

FIG. 6 is a perspective view of the pedometer of FIG. 1;

FIG. 7 is a cross-sectional view taken along line 7—7 of the pedometer of FIG. 1;

FIG. 8 is a top view illustrating our new design for a pedometer according to a second embodiment;

FIG. 9 is a bottom view of the pedometer of FIG. 8;

FIG. 10 is a front view of the pedometer of FIG. 8;

FIG. 11 is a rear view of the pedometer of FIG. 8;

FIG. 12 is a right side elevational view of the pedometer of FIG. 8;

FIG. 13 is a perspective view of the pedometer of FIG. 8;

FIG. 14 is a cross-sectional view taken along line 14—14 of the pedometer of FIG. 8;

FIG. 15 is a top view of the pedometer of FIG. 8 with the cover opened;

FIG. 16 is a bottom view of the pedometer of FIG. 8 with the cover opened;

FIG. 17 is a front view of the pedometer of FIG. 8 with the cover opened; and,

FIG. 18 is a right side elevational view of the pedometer of FIG. 8 with the cover opened.
